UNITED STATES PATENT OFFICE

SAMUEL SEGAL, OF NEW YORK, N. Y.

DESIGN FOR A TWEEZER

Application filed June 6, 1932. Serial No. 43,997. Term of patent 3½ years.

To all whom it may concern:

Be it known that SAMUEL SEGAL, a citizen of the United States, a resident of New York city, county and State of New York, has invented a certain new, original, and ornamental Design for a Tweezer, of which the following is a specification, reference being had to the accompanying drawing, forming a part thereof and in which—

Fig. 1 is a representative showing of both of the side views of the tweezer according to my invention.

Fig. 2 is a front elevational view of the tweezer.

I claim:

The ornamental design for a tweezer substantially as shown and described.

Signed at New York, in the county of New York and State of New York, this 2d day of June, A. D. 1932.

SAMUEL SEGAL.
